[57] CLAIM

The ornamental design for a towel bar, as shown and described.

DESCRIPTION

FIG. 1 is a perspective view of a towel bar incorporating my new design.

FIG. 2 is an enlarged fragmentary top plan view thereof;

FIG. 3 is an enlarged fragmentary front elevational view thereof;

FIG. 4 is an enlarged side view as seen from the upper right in FIG. 1, the other side being identical.
 The rear and bottom surfaces of the towel bar are planar and unornamented.
